SAFETY RAZOR AND BLADE MAGAZINE
THEREFOREdgar A. Nelson, New York, N. Y., assignor to
American Safety Razor Corporation, Brooklyn,
N. Y., a corporation of Virginia

Application October 10, 1945, Serial No. 621,559

10 Claims. (Cl. 30—40)

1
My present invention relates to a safety razor and a blade container for blade placement or replacement in the holder.

Among the general objects of my invention are: a new and improved arrangement in a safety razor for facilitating the placement and replacement of the blade; a new and improved blade dispensing container; and a new and improved means whereby a razor and a blade container can be brought into cooperative relation for dispensing blades from the container directly into the razor.

For the attainment of these objects and such other objects as may hereafter appear or be pointed out, I have illustrated an embodiment of my invention wherein:

Figure 1 is a side elevational view of a razor;

Figure 2 is a top plan view thereof, partly broken away;

Figure 3 is a section taken on line 3—3 of Figure 2;

Figure 4 is a section taken on line 4—4 of Figure 2;

Figure 5 is a top plan view of a blade container with the parts in the position of Figure 7;

Figure 6 is a top plan view thereof, with the cover retracted;

Figure 7 is a cross section taken on line 7—7 of Figure 5;

Figure 8 is a cross section taken on line 8—8 of Figure 7;

Figure 9 is a top plan view of the container and razor assembled for blade placement; and

Figure 10 is a section taken on line 10—10 of Figure 9.

Figures 1 to 4 illustrate a blade holder made in accordance with my invention. It comprises a blade holding assembly 10 and a handle member 11 of any preferred and desired dimensions and contours (see Figure 1). The blade holding assembly in turn is shown as comprised of a saddle member 15 upon which the blade is to be seated and a cap member 16 which holds the blade to its seat.

While the handle member 11 may be secured to the holder in any preferred or desired manner, Figure 4 shows an arrangement wherein the handle member has one or more upwardly projecting lugs 12 received through an opening or openings provided vertically through the saddle member 15 and enlarged at their upper ends as shown at 14 and into which enlargements the lug or lugs 12 may be upset, as shown in that figure, to hold the handle fixed to the saddle with their adjacent faces in abutting relation.

2
The saddle may be provided at its forward or front side with guard teeth 18 of any preferred or desired character. A channel 20 is formed in the upper surface of the saddle and extends for its full length, that is from one end to the other. This channel is defined by side walls 22 and bottom wall 23.

The spaced apart upper surfaces 25 and 26 of the saddle portions 27 and 28 at opposite sides of the channel 20 form the seat for the blades B (see Figure 4).

The blade B which may be either single or double edged is provided with the slot B' (see Figure 2) for cooperation with the means now to be described for locating it on the saddle. While this slot is shown in the drawings as extending longitudinally of the blade and generally oval shaped, it will be understood that its shape and dimensions as shown in the drawings is merely illustrative.

The channel 20 has its bottom 23 provided with a depression 30. Upon comparing Figures 3 and 4 it will be observed that this depression is of less length than channel 20 and terminates short of the opposite ends of said channel. A locating bar 35 is positioned in depression 20. Its conformation and dimensions in horizontal cross-section approximate those of the depression so that it will be free to move vertically in the depression 30, but will be held against lateral or longitudinal movement therein and approximate also these characteristics of slot B' in the blade, so that the locating bar can be received in the same manner also through that slot. The thickness of the locating bar is shown as greater than the depth of the depression 30 for reasons shortly to be pointed out.

A leaf spring 36 seated on the bottom of depression 30 to underlie the locating bar 35 normally holds that bar elevated in the depression (see Figures 3 and 4). The top of the bar 35 is chamfered off at its opposite ends as shown at 38 preferably for a depth to be referred to shortly. The saddle 15 comprises also the thicker portion 39 to the rear of the blade seat portion 28 and defined by vertical wall 40, elevated horizontal longitudinally extending top surface 41, the saddle bottom and the rear and end saddle walls. The cap member has its rear end depressed or channeled out to leave a vertical wall 42 and an elevated bottom face portion 43. These walls and faces are so dimensioned and related that the rear portions of the saddle and cap interfit in the manner shown in Figure 4 and the saddle and cover members are fixed in this relation, prefer-

ably with their end and rear walls matching, by any preferred or desired means such as of rivets 45.

The cover member 16 is shown in Figure 4 as extending forwardly from the wall 42 for substantially the full width of the blade. Its lowermost surface which is shown flat and whose position is fixed by the inter-engaging walls and surfaces 40, 41, 42, and 43 is spaced sufficiently from and above the blade seat defined by the spaced apart upper surface portions 25 and 26 of the saddle member 15, to permit a blade to be entered between the cover and saddle members 15 and 16 and to be held closely on its seat. This blade receiving space between the saddle seat and the lower surface of the cap member extends for the full length of the holder and opens to the exterior through the end walls thereof so that a blade can be entered endwise into said space through either end of the holder until its slot b' is in vertical registration with the locating bar 35 whereupon the top of the locating bar 35 will enter into and engage through this slot. A blade entered endwise into said space through one side of an empty holder will shortly engage the adjacent chamfered or bevelled top corner portion 38 of the bar 35 and gradually depress the bar to the level of the blade seat portions 25 and 26 and hold it depressed as the blade continues to advance until it is fully entered into its position of Figure 3 at which point the aforementioned registration is effected. Reference has been made to the fact that the space provided for the blade between the saddle and cap members is restricted to approximately the thickness of one blade. As a result when the new blade is entered into a holder wherein a used blade is already seated, the advanced end wall of the new blade will abut the adjacent end wall of the already seated old blade and move the old blade along and out of the opposite end of the holder as the new blade is entered thereinto. In this operation, the adjacent end wall portion of slot B' of the old blade will engage the aforementioned adjacent bevelled top corner portion 38 of bar 35 and depress the bar and maintain it depressed until the old blade has been moved beyond the bar. The new blade which is already interposed between the bar 35 and the cap member 16 will hold the bar depressed until it is fully entered and the old blade fully ejected.

The parts including the blade are dimensioned and contoured to effect this registration. The parts are also preferably dimensioned so that when this registration is effected, the sides of the blade will register with the side walls of the holder, its rear longitudinal edge will be adjacent wall 40 and the front shaving edge will be located for effective shaving performance which is determined by the spacing of this edge from the guard and the relation thereto of the cap.

Cover member 16 is shown in Figure 4 as provided on its under surface with the longitudinally extending depression 46 which may also be contoured and dimensioned in horizontal cross section approximately as in the corresponding section through the locating bar 35. Reference has been made to the thickness of this locating bar. This thickness is such that when the bar is elevated by the spring 36 it will engage through the opening B' of a blade seated on the saddle for the full thickness of the blade and will extend therebeyond so that its upper portion will enter the depression 46 on the under surface of the cap

member 16 to serve as a further means for locating the parts.

Figures 5 to 10 of the drawing are intended to show a blade container which has been specially designed as to its details to hold a stack of blades usable in the holder of Figures 1 to 4 in the manner above set forth and to dispense the blades therefrom one at a time directly into the holder. The blade containing space is shown in Figures 7 and 8 as defined by side walls 51 and 52, rear and front walls 53 and 54, bottom 50 and a cover member 56 whose side edges engage in the undercut channels 57 in the side walls, so that the cover can be given a sliding movement to open the container so that it can be refilled through the open top. The container is normally closed except for a blade discharging mouth or opening 58 across the upper portion of front wall 54. This opening 58 is of a height approximately equal to the thickness of the blade and is of a width slightly greater than that of the blade so that the blade can be passed therethrough and from out of the container, without engaging its cutting razor edges with the side walls of mouth 58. The top of the container cover is channeled longitudinally thereof as shown at 59 to seat the operating member 65 of a blade ejector and guide it for sliding movement toward and away from mouth 58. A restricted neck portion 66 attached to and depending from operating member 65 engages through slot 60 formed preferably longitudinally centrally of the channel 59 in cover 56. The height of this neck portion 66 is shown as such that its bottom is below the bottom of the cover 56. Extending forwardly from its bottom is the pusher finger 67, a thickness and width so that it can enter the exit mouth 58. This finger 67 is spaced below the bottom of the operating member 65 for a distance so that when the ejector is moved to its limit to the left the portion 54' of the front wall 54 immediately above the mouth 58 will be received between finger 67 and the bottom of the operating member 65 and the ejecting finger 67 will have entered the mouth 58 to fully eject a blade through that mouth.

A stack of blades are held in assembled relation for successive ejection through mouth 58 by an arrangement such as will now be described. This arrangement comprises two pins 70 riveted to the bottom 50 adjacent opposite ends of the depressed channel 72 which extends lengthwise of the inner surface of the bottom 50. These pins are headed as shown at 71 and the heads are seated on the bottom of this depression 72. The pins 70 engage in opening 75 spaced apart longitudinally of a blade locating bar 76 and springs 77 are spiralled around pins 70 with their lower ends abutting against the heads 71 of the pins and their upper ends abutting against the bottom of the locating bar 76 to hold it elevated with its top surface abutting the bottom surface of the cover 56. The locating bar 76 is of a width no greater than that of depression 72 and is in vertical registration therewith and when elevated terminates above the bottom of the depression 72 to an extent which is at least equal to and preferably in excess of the thickness of a blade.

The locating bar 76 is also dimensioned and contoured in horizontal cross section approximately as are the slots of blade B to be stacked thereon which in the present disclosure are purposefully designed to fit the holder of Figures 1 to 4. Figures 7, 8 and 10 show a stack of blades engaged over this locating bar 76 and held ele-

vated by the laterally spaced fingers 81 and 82 of a flat spring whose base is secured to the bottom 50 of the container preferably to the rear of the depression 72. The spring fingers 81 and 82 engage the blade portions to opposite sides of the slot, as clearly shown in Figure 8.

The locating bar 76 is positioned well forward of the rear wall 53 so that the inner or rear edges of the stacked blade are located a sufficient distance from this rear wall so that the pusher finger 67 in its rearmost position of Figure 7, will be in back of the blade stack and upon reference to this figure, it will be observed that the parts are so dimensioned and related that the pushed finger 67 is aligned with the topmost blade of the stack. The locating bar 76 has the rear top corner edge bevelled or chamfered off as shown at 85 for the purpose shortly to be explained.

When a blade is to be ejected from the container, the member 65 is moved rearwardly to its limit as shown in Figure 7 and is then moved forwardly from that position and in so doing, its finger 67 will engage the topmost blade and push it forwardly. In the initial forward push of the blade, the inner or rear wall of its slot B' will engage and ride over the bevelled portion 25 of the bar and depress it to the level of the bottom of the finger 67 and discharge mouth 58. The intermediate position in this movement is shown in Figure 10. The continued forward movement of operating member 65 in the direction of mouth 58 will push the topmost blade through the mouth 58 and out of the container until the forward end of neck 66 will have engaged the portion of the front wall 54 immediately above mouth 58, and the forward end of the finger 67 will have entered mouth 58 to fully discharge the blade.

Reference has already been made to the fact that the container has been specially designed to hold blades for use in the holder of Figures 1 to 4. An arrangement will now be described whereby the container can be held aligned with the holder so that a blade ejected therefrom in the manner already set forth, will be moved directly into the holder and in so doing will expel a blade which may already be positioned therein. This arrangement comprises a lug 90 which projects forwardly from the front wall 54. The upper face of this lug forms a continuation of the lower wall of the mouth 58; its width equals that of channel 20 in the holder; its length is no greater than and preferably somewhat less than the distance between either end of channel 20 and the adjacent end of the depression 30 in the channel; and its thickness is approximately equal to the depth of the channel 20. As a result, when the lug 90 of the blade container is aligned with either end of the channel 20 of the holder, the lug can be entered thereinto through that end and below a blade that may be seated on the holder saddle. A forward movement of the operating member 65 of the container will move the topmost blade through mouth 58 thereof and along the upper surface of the lug 90 to engage its forward edge either with an old blade already in the razor, eject it from the holder and seat the new blade, or to engage one of the bevels 38 to depress the locating bar 35. The full forward throw of operating member 65 will seat the new blade in the holder in the manner above set forth. It will be observed that lug 90 can be entered into either end of the channel 20 of the holder. Upon reference to Figures 5 and 7, it will be observed that the container front wall 54 is pro-

vided also with forwardly extending lug or platform 92 spaced below lug 90. The upper surface of platform 92 is approximately parallel to the lower surface of lug 90. This spacing of the members 90 and 92 approximately equals the thickness of the portion of the holder saddle which underlies channel 20 so that when lug 90 is entered into one end of the channel, the upper surface of platform 92 will engage the bottom surface of the saddle. This platform 92 extends for the full width of the container and serves as an extended bearing surface to assist in maintaining the container aligned with the holder.

What I claim as new and desire to secure by Letters Patent is:

1. A blade holder comprising a saddle upon which the blade is to be located and a cap overlying said saddle to retain a blade thereon, means to immovably fix said cap to said saddle and space it therefrom to provide a blade receiving space that is open through both end walls of the holder, said saddle having a depression in its upper face which terminates short of both ends thereof, and a blade locating member seated in said depression having the end portions of its upper surface chamfered and means for yieldingly elevating said member to a normal position wherein its upper surface is above the level of the top blade seating surface of the saddle and said chamfered end portions intersect the plane of said surface whereby a blade having a locating opening can be entered into said space through either end of the holder and moved along the saddle to engage the chamfered surface at one end of said locating member to hold it depressed until the blade is fully entered into the holder and the blade opening registered with the member which will be free to rise and engage in said blade opening to fixedly locate the blade in said space.

2. A blade holder comprising a saddle upon which the blade is to be located and a cap overlying said saddle to retain a blade thereon, means to immovably fix said cap to said saddle and space it therefrom to provide a blade receiving space that is open through an end of the holder, said saddle having a depression in its upper face which terminates short of that end, and a blade locating member in said depression having an end portion of its upper surface chamfered and means for yieldingly elevating said member to a normal position wherein its upper surface is above the level of the top blade seating surface of the saddle and said chamfered end portion intersects the plane of that surface, whereby a blade having a locating opening when entered into said space through said end of the holder and moved along the saddle to engage said chamfered surface will depress said member until the blade is fully entered and the blade opening registers with said member which will be free to rise and engage in said blade opening to fixedly locate the blade in said space.

3. A blade holder comprising a saddle upon which the blade is to be located and a cap overlying said saddle to retain a blade thereon, means to immovably fix said cap to said saddle and space it therefrom to provide a blade receiving space that is open through an end of the holder, said saddle having a depression in its upper face which terminates short of that end, and a blade locating member in said depression having an end portion of its upper surface chamfered and means for yieldingly elevating said member to a normal position wherein its upper surface is

above the level of the top blade seating surface of the saddle and said chamfered end portion intersects the plane of that surface, whereby a blade having a locating opening when entered into said space through said end of the holder and moved along the saddle to engage said chamfered surface will depress said member until the blade is fully entered and the blade opening registers with said member which will be free to rise and engage in said blade opening to fixedly locate the blade in said space, and a depression in the underside of the cap which overlies the first mentioned depression and into which said member engages when it is elevated.

4. In combination, a blade holder saddle having a blade seat provided with a channel extending lengthwise of and coterminous with one end of the saddle, and a blade magazine having a discharge mouth in one end wall thereof and a finger projecting forwardly from said wall with its top surface on the level with the bottom of the discharge mouth, said finger being of a thickness approximately equal to the depth of the channel, whereby the finger when entered into one end of the channel will present its upper surface on a level with the blade seat and a blade discharged through said mouth will be guided on to the blade seat.

5. A blade magazine having a discharge mouth in one end wall thereof and a finger projecting forwardly from said wall with its top surface on the level with the bottom of the discharge mouth, and a second finger projecting forwardly from said front wall but spaced below said first finger, whereby a saddle can be engaged in the space between the fingers and a blade discharged from the magazine onto the saddle.

6. In combination, a blade holder saddle having a blade seat provided with a channel extending lengthwise of and coterminous with one end thereof, and a blade magazine having a discharge mouth in one end wall thereof and a pusher slideable along the magazine, said pusher having a forwardly projecting finger to engage in back of and advance a blade from the magazine through said mouth, said finger being dimensioned so that it can pass into said mouth as the pusher is advanced and an elongated member projecting forwardly from said end wall and having its top surface on the level with the bottom of the discharge mouth, said member being of a thickness approximately equal to the depth of the channel, whereby when the member is entered into one end of the channel to present its upper surface on a level with the blade seat, operation of the pusher will expel a blade completely through said opening and onto the blade seat.

7. In combination, a blade holder saddle having a blade seat provided with a channel extending lengthwise of and coterminous with one end thereof, and a blade magazine having a discharge mouth in one end wall thereof and a pusher slideable therealong, said pusher having a forwardly projecting finger to engage and advance a blade from the magazine through said mouth, said finger being dimensioned so that it can pass into said mouth and a member projecting forwardly from said wall and having its top surface on the level with the bottom of the discharge mouth, said member being of a thickness approximately equal to the depth of the channel, and a second member projecting forwardly from said end wall and spaced from said first member for a distance equal to the thickness of the

channeled portion of the saddle, whereby when the first mentioned member is entered into one end of the channel to present its upper surface on a level with the blade seat, said second mentioned member will engage the bottom of the saddle.

8. A blade magazine for holding blades provided with locating openings in stacked relation and for dispensing the topmost blade from the stack, said magazine comprising a casing and spring means therewithin for normally maintaining a blade stack with the topmost blade engaged with the underside of the top wall of the container, means within the container for normally engaging through the registering openings of the stacked blades for maintaining the blades in predetermined stacked relation within the container, said last-mentioned means comprising a blade locating member and spaced means and spring elements for normally maintaining the locating member elevated and also engaged with the underside of the container top wall, a blade discharge opening in an end wall of the container of a height approximately equal to the thickness of a single blade, and positioned on a level with the topmost blade of the stack and a blade expelling member slideable along the container and having a forwardly projecting finger on the level of the blade discharge opening, the top of said locating member being chamfered at its rear whereby the finger of the blade expelling member can engage in back of the topmost blade and push it through the opening as the blade expelling member is advanced to advance the blade and cause a portion thereof to engage the chamfered rear end of the locating member and depress it sufficiently so that the blade can be moved thereabove through said discharge opening and out of the container.

9. A blade magazine for holding blades provided with locating openings in stacked relation for dispensing the topmost blade from the stack, said magazine comprising a casing having front, back and side walls and a top wall, and spring means therewithin for normally maintaining a blade stack with the topmost blade with the underside of the top wall of the container, means within the container registering through the openings of the stacked blades for maintaining the blades in predetermined stacked relation within the container, and with the innermost end of the stack in spaced relation to the rear wall of the container, said last mentioned means comprising a blade locating member and means for normally maintaining the member elevated and also engaged with the underside of the container top wall, a blade discharge opening in the front wall of the container of a height approximately the thickness of a single blade and positioned on a level with the topmost blade of the stack and a blade expelling member slideable along the container and having a forwardly projecting finger on the level of the blade discharge opening, the top of said locating member being chamfered at its rear, the spacing of the rearmost end of the stack from the rear wall of the container being sufficient so that the finger can be moved to a position to the rear of the stack whereby the finger of the blade expelling member when moved to its rearmost position will engage in the rear of the topmost blade and push it through the opening and in so doing will cause a blade portion to engage the chamfered rear end of the locating member to depress that member sufficiently so that the blade can be moved

thereabove through the opening and out of the container.

10. In combination, a blade holder saddle whose top surface presents a seat for the blade and provided with a channel extending lengthwise thereof, said channel being coterminous with and open through one end of the holder and a blade magazine having a finger projecting

forwardly from its front wall, said finger being of a thickness approximately equal to the depth of the channel, whereby the finger when entered into one end of the channel will present its upper surface on a level with the blade seat.

EDGAR A. NELSON.
